DESIGN FOR A NAVIGATION INSTRUMENT

Allen Cameron, Oakland, and Victor H. Kidney,
Alameda, Calif.

Application April 26, 1943, Serial No. 110,043

Term of patent 14 years

To all whom it may concern:

Be it known that we, Allen Cameron and Victor H. Kidney, citizens of the United States of America, residing respectively at 3719 Emerson Street, in the city of Oakland, and 1842 Harvard Drive, in the city of Alameda, both in the county of Alameda and State of California, have invented a new, original, and ornamental Design for a Navigation Instrument, of which the following is a specification, reference being had to the accompanying drawing, forming part thereof.

Fig. 1 is a perspective view of a navigation instrument showing our new design;

Fig. 2 is an elevational view thereof taken from the opposite side of Fig. 1; and

Fig. 3 is an end view.

We claim:

The ornamental design for a navigation instrument, as shown.

ALLEN CAMERON.
VICTOR H. KIDNEY.
